United States Patent Office.

JAMES P. McLEAN, OF BROOKLYN, NEW YORK.

Letters Patent No. 63,072, dated March 19, 1867.

IMPROVEMENT IN PISTON-ROD PACKING.

The Schedule referred to in these Letters Patent and making part of the same.

TO ALL WHOM IT MAY CONCERN:

Be it known that I, JAMES P. McLEAN, of the city of Brooklyn, in the county of Kings, and State of New York, have invented a new and useful Improvement in the Mode of Packing Piston-Rods or shafting by steam introduced through the head of the cylinder into the stuffing-box; and I declare the following to be a full, clear, and exact description thereof, reference being had to the accompanying drawings, which constitute and form a part of the specification, and are lettered to correspond therewith.

In order that the public may fully understand the nature of my invention, and those skilled in the construction and mode of operating the steam engine, I will describe it as follows, to wit:

Figure 1 is a vertical section of an upright cylinder, with piston-rod R and stuffing-box provided with two concave, N, and convex, N', soft metallic or other suitable rings, fashioned so that either section will fit into and press each other horizontally against the piston-rod on one side thereof, and the back of the box on the other or opposite side.

Letter C is a strip or pad of cork, rubber, waste, or other flexible material, placed between the rings N N'. Letters U U are steam ports or openings to admit the steam to pass into and against the under side of the lower ring or packing N', which is provided with a groove, O, to receive the steam or otherwise through the head of the cylinder.

Figure 2 is an enlarged perspective drawing of soft metallic ring packing. These rings may be made of any suitable material that can be operated by the steam without injury.

The advantage over all ordinary packing for piston-rods or shafting, by the above, is, that the steam packs itself by means of the peculiar form of the rings N N', which may be fashioned, if thought best, by dividing the vertical square of the ring packing diagonally, as shown at Figures 3, 4, and 5, or otherwise formed so as to bear upon the piston-rod or shaft when operated by the steam or otherwise. And by the introduction of a flexible substance or body between the rings N N' I am enabled to relieve the rod or shaft R from too great a pressure (caused by the action of the steam) by the elasticity of the pad C.

I am aware that piston-heads have been packed by steam operating upon lugs or other devices arranged in the head of the piston, consequently I do not claim packing the head of the piston by steam; by means of lugs, &c.

But what I claim as new and useful, and what I wish to secure by Letters Patent of the United States of North America, is—

Packing the piston-rod or shafting R of a steam engine with the steam, by means of the sectional rings N N', pad C C, and steam ports U U, constructed and operated substantially as described and shown in the accompanying drawings.

In testimony whereof I hereunto subscribe my name in the presence of two witnesses.

JAMES P. McLEAN.
